UNITED STATES PATENT OFFICE.

FRANK C. MARTIN, OF PLATTSMOUTH, NEBRASKA, ASSIGNOR TO MATHEW F. MARTIN,
OF OMAHA, NEBRASKA.

INTERNAL-COMBUSTION ENGINE.

Application filed May 16, 1921. Serial No. 469,791.

To all whom it may concern:

Be it known that I, FRANK C. MARTIN, a citizen of the United States, residing at Plattsmouth, in the county of Cass and 5 State of Nebraska, have invented certain new and useful Improvements in an Internal-Combustion Engine; and I do hereby declare the following to be a full, clear, and exact description of the invention, such as 10 will enable others skilled in the art to which it appertains to make and use the same.

The object of the invention is to provide an internal combustion or explosion engine of the two-cycle valve-in-head type wherein 15 the cylinders may be built in pairs as in the present approved practice and wherein, while the piston in each cylinder is subjected to the effect of an exploding charge during each forward movement or cycle, 20 a complete and efficient scavenging of the cylinder for the removal of the preceding exploded charge may be effected through the introduction of the new charge which is placed under compression before its admission 25 to the cylinder and which therefore enters the cylinder under conditions adapting it to expand in a direction impelling the explosive charge toward the exhaust port; to provide an engine of the type indicated 30 wherein the explosive mixture is inducted into and placed under compression in an auxiliary or compression cylinder from which it is expelled while under compression into the explosion or power cylinder under 35 conditions assuring a thorough and uniform distribution and intimate mixture of the ingredients,—gas and air, to the end that a perfect and complete combustion is assured when the explosion occurs; and 40 furthermore to provide an engine of compact and simple construction wherein the loss or leakage of pressure during the compression stroke is rendered practically impossible by opposing the compression 45 in the compression or auxiliary cylinder against any tendency to leakage or reduction of pressure from the power or explosion cylinder during the compression stroke of the power piston; and with these objects in 50 view the invention consists in a construction, combination and relation of parts of which a preferred embodiment is illustrated in the accompanying drawings, wherein:

Figure 1 is a side view partly in section 55 of an engine consisting of four cylinders,

Figure 2 is a plan view of the same, Figures 3 and 4 are sectional views respectively on the planes indicated by the lines 3—3 and 4—4 of Figure 1,

Figure 5 is a detail vertical sectional view 60 on the plane indicated by the line 5—5 of Figure 1,

Figure 6 is a detail sectional view of one of the intake valves,

Figure 7 is a similar view of one of the 65 compression or auxiliary cylinder exhaust ports,

Figure 8 is a similar view of one of the explosion cylinder inlet ports.

The main or power cylinders 10 are preferably arranged in pairs as indicated in Figure 1 with their pistons 11 connected by the rod 12 to the crank 13 of the crank shaft 14 arranged in a suitable casing 15 and carrying the usual fly wheel 16. Arranged in 70 supporting coaxial relation with the main or power cylinders are the auxiliary or compression cylinders 17 preferably of larger diameter than the main cylinders and having their pistons or plungers 18 provided 75 with cylindrical extensions or drums 19 in which the piston rods 12 operate and which are of even diameter with the pistons of the main cylinders, said drums or cylindrical extensions 19 operating through packing 80 rings 20 at the lower or inner ends of the main cylinders of which the bases 21 are secured by bolts 22 or the equivalent thereof 85 to the heads 23 of the auxiliary or compression cylinders as shown clearly in detail in Figure 5. The main pistons are provided with the usual or any preferred packing rings 24 and the peripheries of the compression or auxiliary pistons are provided 90 with similar packing rings 25. The main 95 cylinders are provided with exhaust ports 26 communicating with a suitable and preferably common exhaust manifold 27, said exhaust ports being in such a position with relation to the cylinders as to be efficiently 100 exposed when the piston reaches the limit of its downward or inward stroke or cycle as shown in Figure 1.

In the head of each compression or auxiliary cylinder, as indicated in Figure 3 and 105 in detail in Figure 6 there is arranged an intake port 28 which is in valved communication with the intake manifold 29, the valve 30 being of the inwardly opening type held seated by a spring 31 of which 110

the tension may readily be adjusted by means of a suitable nut 32 or the equivalent thereof, the valve being protected by a perforated guard or cage 33 of conical form 5 serving as a spreader and performing the additional function of a mixer or baffle for the explosive mixture supplied by the intake manifold. The cage 33 carries the valve seat 34 and is held in place by a gland 10 nut 35 operating in relation to packing rings 36 and also serving to engage a flange 37 at the inner end of the tubular branch 38 of the intake manifold to insure an efficient and pressure tight joint between the 15 parts, one of the packing rings 36 being arranged between the flange 37 and an annular rib 39 on the cage, and another ring being interposed between the rib 39 and the flange 40 forming the inner wall of the 20 stuffing box which is closed at its outer end as above indicated by the gland nut 35.

During each forward or inward stroke of the compression piston which accompanies the corresponding stroke of the main or power 25 piston, a charge of explosive mixture is inducted into the compression cylinder through the inlet port 28 by the unseating through suction of the valve 30 and hence during the power stroke of the main piston 30 operating under the effect of the explosion of a charge in the main cylinder, and upon the return or outward stroke of the compression piston under the influence of a power or explosion stroke of the companion 35 cylinder of the pair of which it forms a member, the charge of explosive mixture previously received is compressed, and in the compressed condition is forced through a reduced outlet port 41 also formed in the 40 head of the compression cylinder and connected by a pipe or suitable conductor 42 with the feed port of the main or power cylinder forming the other member of the pair of twin or companion cylinders. The 45 liberation of the charge in the compression cylinder and its introduction through the conductor 42 into the companion power cylinder however does not occur until after the same has been compressed by the outward stroke of the compression piston which 50 occurs during the power stroke of the piston in the companion or twin cylinder. For instance, referring to Figure 1 wherein the cylinder units *a* and *b* are shown in section, 55 the piston of the main cylinder of the unit *a* is shown at the uppermost limit of its stroke as when about to receive the impulse of an explosive charge ignitable in any suitable way as by means of a sparking plug 60 for which purpose a seat 43 is formed in the head of the cylinder, while in the unit *b* the pistons are at the innermost limit of their stroke with the compression cylinder having a charge of the explosive mixture inducted 65 thereinto during the inward stroke of the

compression piston 18. The main piston 11 of the unit *b* has just reached the limit of its inward stroke under the influence of the charge exploded in said cylinder and has just exposed the exhaust port 26 while the 70 piston 18 in the companion compression cylinder has compressed its charge and has reached the limit of its upward stroke. The exposure of the exhaust port in the power or main cylinder of the unit *b* thus relieves 75 the pressure in said cylinder to permit of the unseating of the valve 44 which has held back charges of compression cylinder of unit *a*, and thereupon the said compressed charge enters and expands suddenly in the upper 80 end of the main cylinder, being spread throughout the area of the end of the cylinder by the baffling action of the valve, and rushes through the cylinder to expel the burnt gases incident to the exploded charge. 85 Upon the explosion of the charge previously compressed in the main or power cylinder of the unit *a* the relative positions of the parts will be reversed, the piston in the compression cylinder of the unit *a* inducting a 90 fresh charge of the explosive mixture during the stroke of the piston in the power cylinder of the unit *a*, the power piston of the unit *b* compressing the charge of explosive mixture which has previously been introduced 95 thereto and the piston in the compression cylinder of unit *b* compressing the charge previously inducted thereinto ready for discharge through the conductor 42 into the 100 explosion chamber of the main cylinder of unit *a* when the piston in the last named cylinder exposes its exhaust port and thus relieves the pressure upon the valve 44 controlling the feed port of that cylinder.

In order to insure the efficiency of the 105 scavenging action of the fresh charge introduced under compression from the compression cylinder of one unit into the explosion chamber or cylinder of the other unit, the discharge end of the conductor 42 110 is enlarged or expanded as shown at 45 and the valve 44 is located in its closed or seated position flush with the inner surface of the wall of the cylinder as shown clearly in Figure 8, so that when unseated it serves 115 as a spreader or sprayer which discharges the mixture which is introduced under compression in a spread condition serving by its release and consequent expansion to afford a positive and effective impelling force to 120 drive the burnt gases and products of combustion bodily toward the exhaust port which has been exposed by the position of the power piston. The valve 44 is provided with a stem 46 fitted with a seating spring 125 47 of which the tension may be adjusted by means of the nut 48 and the seat for the valve is formed in a cage 49 also of conical form as previously described in reference to the cage 33 with suitable perforations or 130

openings 50 therein to still further induce an intimate mixture of the ingredients of the explosive compound. The cage is provided with a peripheral rib 51 at opposite 5 sides of which are arranged the packing rings 52, one of which rests upon a flange 53 in the wall of the cylinder and the other of which is interposed between a flange 54 formed on the extremity of the funnel or 10 expanded portion 45 of the conductor 42 and the inner end of a gland nut 55.

The end of the conductor 42 which is arranged in communication with the outlet port 41 from the compression cylinder is 15 flanged as shown at 56 and is held in place by a gland nut 57 between which and the flange is interposed a packing ring 58.

Due to the relative arrangement of the elements of each pair of twin or complementary units it will be obvious that the compression strokes taken simultaneously of the main and compression pistons of one unit occur during the power or explosion impelled stroke of the other unit, the charge 25 being introduced to the compression cylinder of the second named unit during the power stroke of its piston, and when the piston of the second named unit reaches the limit of its power or operative stroke and 30 exposes the exhaust port the scavenging charge of fresh gas already in reserve in the compression cylinder of the companion unit is liberated under such conditions as to completely sweep and scavenge the explosion chamber of said second named unit immediately preparatory to the power stroke of the piston in the first named unit, so 35 that the intervals between the periods during which the crank shaft is directly and positively impelled by the power of the explosions are reduced to the minimum and occur only during the passage of the cranks across the dead center positions when the application of power or pressure thereto is 40 useless. The scavenging of each cylinder occurs during the interval in which the piston is in a practically stationary position at the end of its stroke, and during that 45 interval the previously compressed charge

of fresh gas is introduced into the cylinder 50 in which an explosion has just occurred and is permitted to expand and completely fill said cylinder to the substantially perfect exclusion or expulsion of the burnt or spent gases. 55

Having thus described the invention, what I claim is:

An internal combustion engine of the two-cycle type having twin cooperating units each comprising main and auxiliary cylinders and main and auxiliary pistons operative respectively in the main and auxiliary cylinders, the pistons in the twin units moving in opposing relation and connected to a common crank shaft, the auxiliary cylinders 60 being coaxial with and of greater diameter than the main cylinders to provide an annular ledge engaged by the bases of the main cylinders, an intake manifold arranged at one side of the main cylinders and above 65 the auxiliary cylinders and having branches leading into the auxiliary cylinders through openings in said bases and ledges, the openings in said ledges each having an annular flange, valve cages positioned in said openings having annular ribs resting on packing rings carried by the flanges, flanges on the ends of the branches of the intake manifold which extend into the openings, packing 70 nuts clamping said branches and valve cages 75 in place and holding the intake manifold to the engine block, conductors connected with openings in the ledges and having valved communication with the outer ends of the main cylinder, said conductors crossing and 80 leading from the auxiliary cylinder of one unit to the main cylinder of the other unit, and exhaust ports in the sides of the main cylinders and adapted to be uncovered when 85 the main pistons descend a predetermined 90 distance in the cylinders.

In testimony whereof I affix my signature in presence of two witnesses.

FRANK C. MARTIN.
